CODED TRACK CIRCUIT SYSTEM OF
RAILWAY SIGNALING

Robert M. Laurenson, Wilkinsburg, Pa., assignor
to The Union Switch & Signal Company, Swiss-
vale, Pa., a corporation of Pennsylvania

Application August 15, 1941, Serial No. 406,995

7 Claims. (Cl. 246—38)

My invention relates to railway signaling systems of the coded track circuit class, and it has special reference to automatic block and other systems of this character wherein provision is made for approach energizing wayside signals or other traffic governing devices.

Generally stated, the object of my invention is to provide new and improved facilities for approach controlling various functions of coded track circuit signaling systems without the aid of line wires between signal locations.

A more specific object is to reduce the apparatus requirements and increase the utility of approach control facilities of the just defined non-line-wire class.

Another object is to make reset action by those facilities independent of the code following track relays at the entrance ends of the signaled sections.

An additional object is to prevent "kick-back" energy that may be generated in the section rails under shunted conditions thereof from falsely indicating that the circuited section is vacant while a train is still present therein.

A further object is to improve the operation of approach governed systems wherein coded direct current energy for wayside signal control is at times supplemented by coded alternating energy for cab signal control.

In practicing my invention, I attain the above and other objects and advantages by organizing the elements of each coded track circuit combination in a novel and improved manner. In my new organization, pick-up current for the entrance end track relay is supplied from an entrance end source; the code following releases of that relay needed for signal indication selection are produced by neutralizing pulses of signal code energy supplied from an exit end source; an exit end train detector relay normally receives energizing pulses from the entrance end source during the signal code "off" periods; and the normally deenergized approach governed devices are rendered active when and only when transmission of those detector relay energizing pulses becomes discontinued by a shunting of the circuited section rails.

I shall describe several track circuit combinations embodying my invention and shall then point out the novel features thereof in claims. These illustrative embodiments are disclosed in the accompanying drawing in which:

Fig. 1 is a diagrammatic representation of a section of railway track which is equipped with

one preferred form of the approach control facilities of my invention;

Fig. 2 indicates the different forms of energy which are effective in the track circuit of Fig. 1 during vacant conditions thereof;

Fig. 3 is a diagrammatic showing of the approach governing facilities of my invention applied to a track circuit combination wherein coded direct current energy for wayside signal control is at times supplemented by coded alternating current energy for cab signal control; and

Fig. 4 shows how the "polar biased" track relay of each of the Fig. 1 and Fig. 3 track circuit combinations may be replaced by a track relay of the "polar stick" type.

In the several views of the drawing, like reference characters designate corresponding parts. Referring first to Fig. 1, the improved approach control facilities of my invention are there disclosed in association with a coded track circuit system of automatic block signaling for a railway track 1—2 over which it will be assumed that traffic moves in the single direction indicated by the arrow, or from left to right in the diagram.

The protected stretch of this track is divided into the customary successive sections by insulated rail joints 3 and the rails of each section form a part of a new and improved track circuit combination which will be described presently.

In this view of Fig. 1, reference characters D and E respectively designate the entrance and the exit ends of one of these track sections; character TR designates a code following track relay which is installed at the entrance end of the section; character TB a track battery or other direct current source provided at the section exit; character CR a coding device having a contact 5 which periodically connects this track battery in energy supplying relation with the section rails; and character S the usual wayside signal which guards the entrance of each of the track sections and which is controlled by the associated track relay TR through the medium of decoding apparatus DA.

An automatic block signaling system of the referred to code track circuit type operates without the aid of line wires and, in representative form, it includes all of the elements above named. Such a system further comprises the customary facilities (not shown) for continuously operating each of the exit end relays CR at one or another of the usual plurality of distinctive code rates. Selection among these rates (which in a typical three indication system may consist of 75 and

180 energy pulses per minute) is made in accordance with advance traffic conditions by the decoding apparatus DAe functioning in customary manner.

This decoding apparatus (details not shown) is controlled in the usual fashion by the associated track relay TR and it performs the further function of selectively setting up a lighting circuit for one or another of the lamps (G, Y and R in the typical three indication system above referred to) of the wayside signal at the same location. In the arrangement represented, these signal lamps derive energizing current from a power source which is designated by the terminals "plus" and "minus."

In order that certain functions of the signaling system may be rendered active only upon the approach of a train, the apparatus installed at each of the signal locations D, E, and so forth, is supplemented by a train detector relay KR which is arranged to maintain the referred to functions inactive at all times except when the section of track to the rear of the location becomes occupied. In the illustrative arrangement of Fig. 1, only one such approach control function has been provided for and it consists in lighting the wayside signal Se (normally dark) over a contact 9 of the detector relay KR.

When applied to block signaling systems of the "frequency code" character here considered, the improved track circuit facilities of my invention render the relay KR at each signal location responsive to the approach of a train and they do this, moreover, without the use of control line wire between signal locations. Embodied by such facilities are track circuit elements organized in the novel manner which will now be described.

The novel track circuit combination of Fig. 1

Serving to operate the code following and detector track relays TR and KR at the section entrance and exit ends is a track circuit combination of new and improved character. In it, pick-up current for the entrance end track relay TR is supplied from an entrance end source of direct current shown in the form of a track battery KB; the code following releases of that relay which are needed for signal indication selection are produced by neutralizing pulses of signal code energy that are supplied from the exit end source TB over the back point of coding contact 5; the exit end train detector relay KR receives pulses of entrance source energy over the front point of contact 5 during the signal code "off" periods; and the normally deenergized wayside signal Se receives lighting current over back contact 9 when and only when transmission of those detector relay energizing pulses becomes discontinued by the shunting of section D-E's rails.

Examining entrance location D's apparatus in greater detail it will be seen that the direct current source KB is continuously connected across the section rails through a circuit which includes an impedance 12. By this connection there is established between the rails a difference of potential having the positive or "given" polarity character represented by the "KB potential" portion of Fig. 2.

The entrance end track relay TR is bridged across these rails through the usual impedance 13 and hence has impressed thereon the voltage of source KB reduced only by the potential drops which occur in impedances 12 and 13. In the

illustrative form shown, this relay is a code following device of a well known "polar-biased" type which can be picked up only by "given" polarity potential received from the section rails but not by potential of the opposing polarity.

In Fig. 1 the latter characteristic is designated by the polarity markings near the terminals of relay TR. These markings, it will be noted, coincide with those near the terminals of the entrance end direct current source KB and also with those for the section rails 1-2 at the entrance location D. Relay TR is, in consequence, normally held picked up by the given polarity potential from the source KB.

Examining next the apparatus at the exit end location E, it will be seen that the direct current source TB thereat is by coding contact 5 of device CR connected with the section rails in such manner as to supply them with energy which makes rail 2 positive with respect to rail 1. This energy polarity directly opposes that of the entrance end source KB and reacts thereon in a manner to be described presently.

In periodically operating as aforesaid, coding device CR's contact 5 thus connects the exit end source TB with the section rails in a manner to supply them with "on" period pulses of opposing polarity energy that are separated by "off" period intervals. This pulsed signal control energy is passed through the usual current limiting impedance 15 and it has the recurring cycle character which the "TB-CR code" portion of Fig. 2 represents.

As earlier mentioned, the exit end detector relay KR is connected with the section rails during and only during the "off" periods of the just described signal control code. Producing this recurrent connection is the coding contact 5 (front point) and included therein is an impedance 16.

For a purpose later to be made evident the relay KR is sufficiently slow releasing to bridge the "on" code periods by which the just named "off" period connections are separated. For producing this release delay use may, of course, be made of any suitable means such as a snubbing impedance (not shown) bridged across the winding terminals or internal design expedients incorporated in the relay.

Operation of the Fig. 1 combination

Under the represented vacant conditions of section D-E, the entrance end track relay TR recurrently picks up and releases in step with the code following operation of the exit end coder device CR. Unlike conventional systems, however, each "on" period of signal code energy from exit end source TB is accompanied by a release of track relay TR and each "off" period of the same code is accompanied by a pick-up of the track relay.

The reason for this will become more evident upon reference to Fig. 2. Diagrammed by the upper portion thereof is the positive or "given" polarity potential which entrance source KB impresses upon the section rails; diagrammed by the "TB-CR code" portion is the pulsed negative or "opposite" polarity potential which the rails receive from the exit end signal code apparatus; and diagrammed by the lower portion is the resultant trackway potential which becomes effective for energizing the entrance end track relay TR and also the exit end detector relay KR.

Energy is supplied from battery KB through

resistor 12 to two branch circuits in multiple. One of these branch circuits includes in series therewith the winding of track relay TR and the resistor 13. The other or second branch circuit includes in series therewith the track rails and equipment at the exit end of the section. When contact 5 of coding relay CR is picked up the winding of relay KR is connected across the section rails in series with resistor 16, and is therefore included in series with the second branch circuit to which energy is supplied from battery KB. The various elements of the track circuit apparatus are arranged and proportioned so that under the most adverse ballast conditions sufficient energy is supplied to both relays TR and KR to pick up their contacts.

On movement of the contact 5 of relay CR to its released position, the relay KR is disconnected from the section rails, while the battery TB is connected across the section rails in series with resistor 15. Accordingly, the battery TB is now connected in the second branch circuit referred to above. The battery TB and resistor 15 may be of lower resistance than the winding of relay KR and resistance 16, and when the battery TB and resistance 15 are substituted for relay KR and resistance 16 in the second branch circuit identified above, there is an increase in flow of energy from the battery KB in this branch circuit and an accompanying decrease in the flow of energy from the battery KB to the other branch circuit, that is the branch circuit which includes the winding of track relay TR.

In addition, when battery TB is connected across the track rails energy is supplied therefrom over the track rails to the entrance end of the track section, where this energy divides between two branch circuits. One of these branch circuits includes in series therewith the resistor 13 and the winding of track relay TR, while the other branch path includes in series therewith resistor 12 and battery KB. The battery TB is included in the circuit in such manner that the energy supplied therefrom to relay TR flows through the winding of relay TR in the opposite direction to the energy supplied from battery KB to the section rails. The various elements of the combination are arranged and proportioned so that the energy supplied from battery TB to relay TR sufficiently offsets that supplied from battery KB to effect release of the relay contacts.

On subsequent movement of contact 5 of relay CR to its picked-up position, the battery TB ceases to be connected across the section rails, while relay KR is again connected across the section rails. Accordingly, energy is no longer supplied from battery TB to relay TR, while energy from battery KB is again supplied to relays TR and KR and the contacts of relay TR pick up, and the contacts of relay KR remain picked up.

Accordingly, on continued code following operation of the relay CR, energy from the battery KB picks up the track relay TR and energizes the relay KR during the picked-up periods of contact 5, while during the released periods of contact 5 energy from battery TB feeds to relay TR and causes its contacts to release.

Whereas, however, relay TR follows code, the exit detector relay KR remains continuously picked up under these vacant section conditions. As earlier stated, this continuous pick-up is due to relay KR having sufficient release delay to 75

bridge the "on" code periods by which its recurrent energizing pulses are separated.

Nor do changes in frequency of signal control code pulse recurrence alter the action just explained. Operation of the complete signaling system of which the Fig. 1 track circuit forms a part involves, of course, such changes. In the three indication organization earlier referred to "clear" and "approach" codes of 180 and 75 cycles per minute are typical.

For either of these code speeds (and also during others which the system may utilize) my improved track circuit combination is found to operate in the desired manner earlier described, 15 wherein the entrance track relay TR follows code at a rate which determines the signal indication and the exit end detector relay KR holds contact 9 continuously picked up. Because of that picked up condition the approach governed signal Se is normally maintained inactive.

Upon entry of a train into section D—E the accompanying shunt of the section rails removes energizing current from both the entrance relay TR and the exit relay KR. In now releasing, 20 the latter device completes over its contact 9 the lighting circuit for wayside signal Se and thereby causes that signal to display to the train the indication which advance traffic conditions determine. Such display, quite obviously, continues 30 as long as any part of the train remains in the section D—E.

Upon departure of the train from the section the resulting shunt removal allows the positive or given polarity potential from entrance source 35 KB again to appear between the rails and also allows the "on" period pulses of opposite polarity signal control energy to be transmitted thereover from the section exit. The train departure is, in consequence, accompanied by an immediate 40 pick-up of entrance relay TR and restoration of that relay to its normal code following condition. Further accompanying that departure is a prompt reception by exit detector relay KR of "off" period pulses of pick-up energy from entrance source 45 KB. By those pulses relay KR is held picked up and contact 9 thereof now restores approach controlled signal Se to its normally inactive state.

It is to be noted that the just described response of detector relay KR to the train departure is completely independent of the entrance end track relay TR and even were device TR to be removed from the combination the response would take place in the manner intended. This is because of the continuous connection of entrance source KB across the section rails and the direct availability of this potential for picking up relay KR once the section rails become unshunted.

In addition to the obvious advantage of absolute reliability, the just explained characteristic reduces the apparatus requirement of non-line-wire approach control facilities for coded track circuits. Past commercial provisions of such facilities are typified by the "coded feed back" organization which is disclosed and claimed by Herman G. Blosser Reissue Patent No. 21,783. In the track circuit combination of that patent, use is made of an impulse relay IR (not here shown) which is required at the section entrance end to transfer the rail connection from the track relay TR to the feed back source AB (corresponding to source KB hereof) during each "off" period of the received signal control code. By eliminating the need for such an impulse relay, the

improved combination of my invention effects important savings in track circuit apparatus.

The track circuit organization of Fig. 3

Consideration of the polarities which are necessary to make the Fig. 1 track circuit operable shows that they have the opposing entrance and exit source relations earlier pointed out in detail. This is the desirable polarity from the standpoint of safeguarding the exit detector relay KR from false operation in the event of an accidental bridging of the front and back points of coder relay CR's contact 5.

It is, however, undesirable from the standpoint of safeguarding the detector relay KR from false operation due to inductive "kick-back" energy which may be generated in the rails 1-2 of the direct current track circuit D-E when those rails are shunted by a train. When so generated this energy appears in the rails at the end of each "on" period pulse of the unidirectional current with which source TB supplies the trackway over the back point of coding contact 5.

Direct current track circuits employing detector relays of the type shown at KR can experience serious operating difficulties due to such "kick-back" energy and one early proposal to overcome such difficulties forms the subject of assignee's Patent 2,286,002, which issued to Frank H. Nicholson on June 9, 1942.

As the specification of that patent sets forth in considerable detail, "kick-back" energy of the type here considered results from the inductance of the track circuit plus the conductance of the rail-to-rail ballast and its effect is to continue for a short interval after each disconnection of direct current source TB from the section rails the flow of current in those rails in the same direction as was established by source TB.

Hence, when the rails of Fig. 1's section D-E are shunted by a train each "on" period pulse of trackway current which source TB impresses upon those rails thus may be followed by a "kick-back" energy pulse which though relatively short still is of sufficient duration to overlap the early portion of the succeeding "off" code period. Current due to these overlapping pulses thus may reach relay KR over the front point of coding contact 5 and if of sufficient magnitude such "off" period current may falsely pick up relay KR even though the signal Se approach controlled thereby should stay lighted until the train has cleared the section.

In order to reduce the possibility of this trouble and provide additional simplification, the circuit shown in Fig. 3 may be utilized. In its basic organization it duplicates the earlier described combination of Fig. 1. Thus, the entrance end portions at location D are exactly the same in both instances and the exit end portions at location E differ only in that: (1) the train detector track relay has the form of a code following device KR1; (2) the approach lighting contact 9 is carried by a slow release repeater AR which derives pick-up current over a contact 18 of relay KR1; (3) the circuit over which source TB supplies direct current to the track rails includes a contact 19 of relay AR; and (4) provision is made for at times supplying the section rails with coded alternating energy for cab signal control.

This provision is shown as taking the form of a track transformer TT having a secondary winding connectable with the rail supply circuit over the back point of contact 19 and having a primary

winding which is connected with a source B-C of 100 cycle per second or other commercial carrier wave frequency alternating current energy.

These alternating current energy supply facilities will, quite obviously, be provided only when the signaled track is to carry vehicles which are equipped with cab signaling equipment and insofar as the "kick-back" energy is concerned, they either may or may not be used. Further consideration thereof will, accordingly, be reserved for a later part of this description.

In its broader aspects the supplemented track circuit combination of Fig. 3 duplicates the operation of the Fig. 1 combination. That is, vacant conditions of the circuited section D-E are accompanied by a code following action of entrance track relay TR and "off" period energizations of the exit detector relay KR1. Instead, however, of staying continuously picked up as does device KR of Fig. 1, relay KR1 of Fig. 3 picks up and releases its contact 18 in step with the "off" and the "on" periods of the direct current signal control code that results from contact 5's recurrent connection of exit source TB with the section rails.

The repeater or approach relay AR is, in consequence, recurrently energized from the local source "plus"-minus" and, due to its slow releasing characteristics, it holds contacts 9 and 19 continuously picked up. This insures the desired deenergization of the approach control signal Se and also keeps the direct current source TB included in the rail supply circuit.

Entry of a train into Fig. 3's section D-E, deenergizes and hence continuously releases both the entrance track relay TR and the exit detector relay KR1. By the latter release, approach relay AR becomes continuously deenergized and hence drops contacts 9-19. That action causes lighting current to be supplied to signal Se and also removes (at contact 19) the direct current source TB from the rail supply circuit of which coding contact 5 forms a part.

By that removal, all coded direct current energy is prevented from reaching the section rails and all possibility of "kick-back" energy generation is thereby removed. The kick-back energy thus having been eliminated, the detector relay KR1 is no longer subject to false energization under occupied conditions of the rearwardly extending section and the problem earlier discussed is thereby fully and satisfactorily solved.

Nor does this solution in any way interfere with other operating characteristics of the supplemented track circuit. As long as the circuited section remains occupied there is no necessity for any supply of coded direct current energy thereto, and when the train clears the section's exit end E this supply of direct current coded energy is promptly restored to the rails.

Such restoration results, in the organization of Fig. 3, from the flow of entrance end energy from source KB to the winding of detector relay KR1 over the now unshunted rails and the front point of exit contact 5. By that flow, contact 18 is picked up to energize the repeater relay AR and cause its contact 19 to reinsert the direct current source TB into the rail supply circuit.

Such reinsertion, quite obviously, occurs very quickly and thus assures that each clearance of the circuited section will promptly be followed by a pick-up of contact 19 and an attendant res-

toration of coded direct current energy to the section rails.

Once so restored the "on" period pulses of signal control energy produce code following operation on the part of entrance track relay TR and thereby continues the track circuit combination in its normal or vacant section condition until another train comes into the section. In the particular organization of Fig. 3, each of the named "on" period pulses is impressed upon the section rails by way of a circuit extending from the positive terminal of direct current source TB through conductor 21, track rails 1 and 2, conductor 22, back contact 5 of device CR, conductor 23, front contact 19 of device AR and impedance 15 back to the negative terminal of source TB.

Because of the continuous connection of the entrance source KB with the section rails, the code reproduction by the detector relay KR1 is completely independent of relay TR and it is because of this characteristic that removal of all coded direct current energy is possible under occupied conditions of the section.

As shown in Fig. 3, contact 19 by which this removal is effected is carried by a slow release approach relay AR. The same results may, quite obviously, be achieved by making the detector relay KR1 a slow acting device, as in Fig. 1 (relay KR thereof), and placing contact 19 directly thereon. With such a combination, each entry of a train into the circuited section again releases contact 19 and thereby removes the direct current source TB from the rail energizing circuit. Such removal continues until the section is cleared by the train at which time relay KR receives pick-up current from entrance source KB and directly causes contact 19 to reinsert source TB into the coding supply circuit of which contact 5 forms part.

Returning now to the cab signal supply elements B-C and TT of Fig. 3, these are inactive under all vacant conditions of section D-E and are so continued by the normally picked up contact 19 of device AR. When, however, the section becomes occupied by a train, the resulting release of contact 19 first moves direct current source TB from the rail supply circuit and then includes the secondary of transformer TT therein.

Under conditions of such inclusion, each movement of device CR's contact 5 to its lowermost position causes the section rails to be supplied with a pulse of alternating current energy from source B-C. The circuit over which this supply takes place may be traced from the right-hand terminal of transformer TT's secondary through back contact 19 of device AR, conductor 23, back contact 5 of device CR, conductor 22, track rails 1 and 2 and conductor 21 back to the left terminal of the TT transformer secondary.

The resulting coded alternating current energy has the same suitability for controlling train carried cab signals as were it to be supplied over exit end circuits of conventional character. The frequency of its pulse recurrence is, quite obviously, dependent upon the rate which coding relay CR operates contact 5, and that rate, as already pointed out, is determined by conditions of traffic in advance of the supply location E.

Once instituted, moreover, the coded alternating current supply continues until the rearwardly extending section D-E becomes cleared by the train. When that happens, relay AR's contact 19 picks up and in so doing it removes

the transformer TT from the rail supply circuit and reinserts the direct current source TB therein. As long as the section remains vacant, coded direct current and only direct current energy is supplied to its rails.

The just described separation of the direct current trackway energy from the alternating current cab signal energy by contact 19 of the train detector repeater is made possible by my earlier disclosed novel combination of the detector track relay KR with the entrance end source KB that is continuously connected across the section rails. As tests in the field have indicated that the major portion of the earlier mentioned "kick-back" energy is due to direct current code pulses, the named separation results in a substantial reduction in the kick-back effect that is present in combination where coded direct current for wayside signal control is at times supplemented by coded alternating current energy for cab signal control.

Further desirable results also accrue from the named separation. Tests on a 6000 foot track circuit show that about 15 or 20% of the required 100 cycle cab signal energy is expanded in a track limiting resistor of the character shown at 15 when such a resistor is included, as has been necessary in the past, in the cab signal supply circuit. Fig. 3's elimination of that resistor from the circuit therefore effects marked economies in cab signal power requirements and it also saves wear and tear on conventional tuned alternators (not shown) when such are used to provide the 100 cycle alternating current from direct current sources of the track or control battery type.

Since, moreover, the named separation removes all short circuit drain from the track battery TB, the wear on coding device CR's contact 5 is substantially reduced. Still further, the separation function can be performed without requiring additional contacts on the approach relay AR of conventional exit end combinations of approach control apparatus. In such conventional combinations, a contact is customarily used to short circuit the track transformer TT under vacant conditions of the rearwardly extending section. With the improved arrangement shown in Fig. 3, such short circuiting no longer becomes necessary and the contacts which ordinarily would perform it may therefore become available for use as element 19.

"Polar stick" track relay of Fig. 4

Track relays TR of the conventional "polar biased" type have been shown and described as forming parts of each of the track circuit combinations of Figs. 1 and 3. As earlier pointed out, the contacts (not shown) of such relays can be picked up only by "given" polarity trackway potential but not by potential of the opposing polarity. When, moreover, the "KB-TB potential" of Fig. 2 has the completely balanced character (no reversal by the opposing polarity "on" periods) which that figure shows, track relays of the "neutral" or non-polar type will operate satisfactorily in each of the track circuit combinations of Figs. 1 and 3.

Still further types of code following track relays also are usable in those combinations and one of these is shown by Fig. 4 as taking the form of a "polar stick" device TR1. Such a device has contacts (see element 30) which occupy the left or "normal" position when and after positive or normal polarity potential is applied

to the relay winding and which occupy the right or "reversed" position when and after the relay winding receives negative or reversed polarity potential. To shift these contacts from one position to the other the potential applied to the relay winding must not only be reduced to zero but it must also be built up in the opposing polarity direction.

Assume now that the "polar biased" track relay TR of Fig. 1 is replaced by the "polar stick" track relay TR¹ of Fig. 4. The "normal" polarity potential from entrance source KB will, quite obviously, hold relay TR¹'s contact 30 in the left or normal position. That positioning will continue, moreover, until opposing polarity potential is applied to the relay winding.

In the particular energy relations which Fig. 2 shows, such opposing polarity application will not, however, take place for the reason that each "on" period pulse of "TB-CR code" potential from opposing polarity source TB merely neutralizes the normal potential from source KB but does not provide any opposing polarity excess for track relay energization.

If, however, the voltage of source TB be raised (or if certain other track circuit adjustments be made), then an excess of opposite polarity potential will appear at entrance location D during the "on" code periods and track relay TR¹ will by that excess potential have its contacts shifted to the right or reverse position during each of those "on" periods.

Under those conditions "polar stick" track relay TR¹ will follow code in the desired manner and its contacts then can be used to operate decoding apparatus D-A in the same way as do those of "polar biased" track relay TR. That track relay TR of Fig. 1 can, therefore, be replaced by the "polar stick" track relay TR¹ of Fig. 4 without interfering with the basic operation of the Fig. 1 track circuit combination.

As will now be evident, a similar substitution may be made in the Fig. 3 combination—if the energy-supply elements thereof be so adjusted that each "on" period pulse of opposing polarity energy from source TB not only overcomes the normal polarity potential from source KB but also provides an excess of opposing polarity potential for track relay energization.

Summary

Regardless of the type of track relay used, the herein disclosed circuit organizations of Figs. 1 and 3 both eliminate the necessity for an entrance end impulse relay of the character shown at IR in the Blosser Reissue Patent No. 21,783 plus that relay's transformer energizing facilities. Both further eliminate the time lost in picking up such an impulse relay during each "off" period of the received signal control code.

This latter elimination assures that the pulses of entrance end energy which reach the exit end detector relay KR will be of the full "off" period length instead of being of the relatively short character shown at "k" in Fig. 3 of Edward U. Thomas Patent No. 2,172,893. Because of this lengthening, all need for the detector relay stick circuits of the Thomas patent type is eliminated and code following detector relays may, therefore, take the simplified form shown at KR¹ in Fig. 3 of the present application.

Such elimination, furthermore, means that in a repeater relay combination of the type shown in Fig. 3 the slow release device KR may effectively be energized over a simple circuit of the

direct controlled type shown. Since relay KR¹ has substantially equal pick-up and release times, the limitations on the minimum release delay of the repeater AR are widened. That relay can, therefore, be designed to consume less energy and be made with a shorter release time which will improve block joint shunting response. Furthermore, it can be operated from the conventional line battery, if desirable.

While it is true that some of the foregoing advantages are obtained at the expense of a somewhat increased track battery drain, the effective "local" energization of the entrance end track relay TR gives some compensation for this added drain, as does also the elimination of the requirement for a stick circuit on exit end detector relays of the code following type shown at KR¹ in Fig. 3.

While I have explained my invention in applications wherein the lights of wayside signals (Fig. 20 1 and Fig. 3) and the cab signal control energy supply only are approach controlled, it will be understood that it has equal utility when used with approach control combinations which provide for other comparable functions instead of or 25 in addition to the illustrative ones just named. One such further function might consist in operating highway crossing signals (not here shown) or the like; a second in the approach lighting of station platform lights; and a third in the locking 30 of track switches at crossovers in automatic territory.

From the foregoing it will accordingly be seen that I have made substantial improvements in the 35 art of approach controlling railway signaling systems of the coded track circuit class. More specifically: (1) I have reduced the apparatus requirements and increased the utility of approach 40 control facilities of the non-line-wire coded system class; (2) I have made reset action by those facilities independent of the code following track 45 relays at the entrance end of the signaled section; (3) I have prevented "kick-back" energy that may be generated in the section rails under shunted conditions thereof from falsely indicating 50 that the circuited section is vacant while a train is still present therein; and (4) I have improved the operation of approach governed systems wherein coded direct current energy for wayside signal control is at times supplemented by coded alternating current energy for cab signal control.

Although I have herein shown and described 55 only two forms of approach control combinations embodying my invention, it is understood that various changes and modifications may be made therein within the scope of the appended claims without departing from the spirit and scope of my invention.

Having thus described my invention, what I 60 claim is:

1. In a coded railway signaling system, in combination, a section of railway track through which traffic normally moves in a given direction, a track relay at the entrance end of said track section having its winding connected across the section rails, an approach relay and a first battery located at the exit end of the track section, a coding device having a contact continuously actuated between a first position and a second position, means for connecting said approach relay across the section rails when said coding device contact is in its first position, means for connecting said first battery across the section rails when 65 said coding device contact is in its second position, and means for connecting said approach relay across the section rails when said coding device contact is in its first position, means for connecting said first battery across the section rails when 70 said coding device contact is in its second position.

tion, and a second battery located at the entrance end of said track section, said second battery being connected across the section rails in multiple with said track relay and being arranged to supply to said track relay energy of a polarity and of a value effective to cause the track relay contacts to move from their first to their second positions and to also supply to the track rails energy which when supplied to the approach relay is effective to operate said relay, said first battery being effective when connected across the section rails to supply to said track relay energy of a polarity opposite to that supplied to said track relay from said second battery and of a value effective to cause movement of the track relay contacts from their second to their first positions.

2. In a coded railway signaling system, in combination, a section of railway track through which traffic normally moves in a given direction, a code following track relay at the entrance end of said track section having its winding connected across the section rails in series with a first resistor, a first battery located at the entrance end of said track section, said first battery being connected through a second resistor to a first branch circuit including in series therewith said first resistor and the winding of said track relay and to a second branch circuit including the section rails in series therewith, an approach relay and a second battery located at the exit end of the track section, a coding device having a contact which is continuously actuated between a first and a second position, means for connecting said approach relay across the section rails when said coding device contact is in its first position, and means for connecting said second battery across the section rails when said coding device contact is in its second position, the elements of the combination being arranged and proportioned so that when the section is vacant and the coding device contact connects the approach relay across the section rails energy is supplied from said first battery over said section rails and operates said approach relay and is also supplied from said first battery to the track relay and flows through the track relay winding in a given direction and causes the track relay contacts to move from their first to their second position, the elements of the combination also being arranged and proportioned so that when the section is vacant and the coding device contact connects said second battery across the section rails energy is supplied from said second battery over the section rails and flows through the winding of the track relay in the reverse of said given direction and causes the track relay contacts to move from their second to their first position.

3. In a coded railway signaling system, in combination, a section of railway track having a first and a second track rail over which traffic normally moves in a given direction, a code following track relay located at the entrance end of said section, the winding of said track relay being connected across the section rails in series with a first resistor with the first terminal of said winding connected to the first track rail, said track relay having a contact which when in its first position is moved to its second position when and only when energy flows through the relay winding from its first to its second terminal, a first battery located at the entrance end of said section, said battery being connected through a second resistor across the track rails and also across the terminals of the track relay winding in series with

- 75 said first resistor, the positive terminal of said first battery being connected to the first terminal of the track relay winding, an approach relay and a second battery located at the exit end of said section, a coding device having a contact continuously actuated between a first and a second position, means for connecting said approach relay across the section rails when said coding device contact is in its first position, and means effective 5 when said coding device contact is in its second position to connect said second battery across the section rails with the positive terminal of said battery connected to said second track rail so that energy supplied from said second battery to the track relay winding flows through said winding from its second to its first terminal, the elements of the combination being proportioned so that when the section is vacant and the coding device contact connects the approach relay across the section rails energy from the first battery operates the approach relay and causes the contacts of the track relay to move from their second to their first position.

5. In a coded track circuit signaling system for

railroads, a code transmitting and receiving means comprising a code following detector relay, a slow releasing relay governed by said detector relay, a track battery, and a coding device having a contact continuously actuated between a first position in which it establishes a circuit including a front contact of said slow releasing relay for connecting said track battery across the rails of a section of a track section and a second position in which it connects the winding of said detector relay across said rails.

6. In a coded track circuit signaling system for railroads, a code transmitting and receiving means comprising a code following detector relay, a slow releasing relay governed by said detector relay, a track battery, a track transformer, and a relay, a coding device having a contact continuously actuated between a first and a second position, said coding device contact being effective when in its first position to establish a circuit to connect said track battery or the secondary winding of said track transformer across the rails of a section of

railway track according as the contacts of said slow releasing relay are picked up or released, said coding device contact being effective when in its second position to connect the winding of said detector relay across said rails.

7. In a coded track circuit signaling system, a code transmitting and receiving means comprising a code following detector relay, a slow releasing relay governed by said detector relay and having contacts which are picked up when and only when said detector relay is responding to energy supplied over the rails of a track section, and a coding device having a contact continuously actuated between a first and a second position, said coding device contact being effective when in its first position provided the contacts of said slow releasing relay are picked up to connect a source of current across the rails of a track section and being effective when in its second position to connect the winding of said detector relay across said rails.

ROBERT M. LAURENSEN.
